J. LEDWINKA

DOVETAIL CONSTRUCTION FOR VEHICLE DOORS

Filed Oct. 2, 1924

INVENTOR.
JOSEPH LEDWINKA

BY

John P. Farley
ATTORNEY.

UNITED STATES PATENT OFFICE.

JOSEPH LEDWINKA, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA.

DOVETAIL CONSTRUCTION FOR VEHICLE DOORS.

Application filed October 2, 1924. Serial No. 741,259.

The dovetail construction of my invention is adapted particularly for embodiment in connection with automobile bodies of pressed metal construction. The problems 5 of accurate and self-adjusting dovetailing and of noiseless engagement are particularly acute in bodies of this class. My invention aims to meet these problems in a wholly efficacious and yet most simple way.

10 Briefly stated, I constitute the dovetail sockets in which the dovetailing heads are to be seated of a yielding structure, embodying a sound-deadening material so disposed that it not only deadens the sound but 15 at the same time renders the sockets, by reason of its resiliency, self-adjusting as to size and to sufficient extent to accommodate the dovetailing heads in thickness adjustment after they have become considerably 20 worn. These sockets I mount in place by the simplest sort of a screw clip.

In the accompanying drawings I show that form of my invention now best known to me. Fig. 1 is a side elevation of an automobile body in which my invention is embodied.

Fig. 2 is a cross-section of the doors of that body and the associated door post on line 2—2, marking the point at which the 30 embodiment is made.

Fig. 3 is a sectional elevation on line 3—3 of Fig. 2.

Fig. 4 is a partial longitudinal section of the dovetail sockets on line 4—4 of Fig. 3. 35 The body shown in Fig. 1 is of the closed body type commonly called a sedan. It embodies two doors 10 and 11 which close toward each other upon an intermediate body post commonly called a B and C post, 40 and so designated here. The post as shown in Fig. 2 is of channel shaped cross-section comprising a bottom wall 12 and side walls 13 and 14 respectively. The side walls are offset intermediate their edges as at the 45 points 15. Confined interiorly of the posts 12 in these offsets are the dovetail sockets designated generally 16, one set for each door. These sockets are engaged by the dovetailing heads 17 carried by the doors 10 and 50 11. The doors comprise jamb rails 18 offset intermediate their edges correspondingly to the side walls 13 and 14 of the post. The dovetail heads are formed in pairs in the shape of a forging or casting and secured by

bolting their bases 19 to the interior of the 55 inner portion of the jamb rails 18 in a position to project their heads through apertures formed in the jamb rails beside and beyond the offset portions 18' of the rails. They are thus in a position to engage the sockets 60 when the door is closed, as indicated in Fig. 1 and through this engagement, to align the door horizontally for proper and most effective closure and the proper operation of 65 its locks.

The dovetail sockets 16 comprise a pair of spaced U-shaped clips 20, arranged with the open ends thereof facing toward the offsets 15 of the post walls. They present at openings 21 in these walls through which 70 the heads 17 may enter the mouths of the sockets. These openings 21 are of greater height than thickness of the heads 17, but the mouths of members 20 are of less width, whereby when the head engages within them 75 the lips of the socket members 20 are engaged by the faces of heads 17 and forced apart. Faces of heads 17 are tapered toward each other inwardly, whereby an easy entry and gradual forcing apart of the lips 22 of 80 members 20 is attained. These lips themselves are turned laterally to form lateral flanges 23. The bites of the U-shaped clips 20 are enlarged jointly to give a greater resiliency to the clip itself, which is made 85 of resilient material and to confine the engagement of the dovetails largely to the mouths of the clips.

Between the pairs of clips and on the outside of each pair there are provided resilient 90 and yielding rubber blocks 24, which function jointly to increase the pressure behind the walls of sockets 20 and which tend to cushion and render noiseless the engagement thereof by the faces of the heads 17. There 95 are three of these rubber blocks of substantial dimensions and contours conforming to the contours of the clips forming the sockets 20, one between the clips and one at each end of the pair. The complete assemblage 100 is confined in place by socket retaining clip 25 secured to the side wall of the post at each end and at its middle, being provided with end and side tabs 26 and 27 respectively for that purpose. Moreover, the edges 105 of this clip are respectively inturned at 28 and 29 to form confining side walls for the clips 20 and blocks 24, the walls engaging

the sides of the blocks, and the heads and lip flanges respectively of the clips 20. The exterior flange 28 extends almost to the side walls 13, 14 of the post channel, while the 5 interior flanges 29 extend only to the inner edge of the apertures 21 through which the dovetail heads enter the sockets. The blocks 24 and the clips 20 are confined at their lower interior edges within the angle of the off-
sets 15.

10 So organized, the entire structure may be most readily attached and detached by removing the secured screws which are applied from the exterior of the door post. The 15 metallic clips 20 forming the sockets proper take the wear of engagement with the dovetail, the rubber blocks 24 supplement the resiliency of the clips, increase the firmness of the socket, improve its shock-absorbing 20 qualities, and lastly, but of considerable importance, thoroughly damp out noise incident to the engagement of metal upon metal which proves so highly objectionable in most types of dovetails known to the art.
25 All modifications of my invention which do not depart from its generic spirit should fall within the purview of the annexed claims.

What I claim is:

30 1. A twin dove tail construction compris-

ing a housing having twin apertures adapted to receive a pair of dove tails, U-shaped spaced metallic wearing clips flanking the apertures and adapted to contact with the received dove tails, resilient means 35 between the endmost of said clips and the ends of the housing, and additional resilient means floating freely centrally of the housing between the spaced clips.

2. A twin dove tail construction comprising 40 a housing having twin apertures adapted to receive a pair of dove tails, U-shaped resilient wearing clips flanking the apertures and adapted to contact with the received dove tails, resilient means between 45 the endmost of said clips and the ends of the housing, and additional resilient means floating freely centrally of the housing between the spaced clips.

3. An anti-rattling structure for doors and 50 the like comprising a door post having a jamb portion substantially of Z shaped cross section, and a dove tail socket arranged in the inner angle of the Z and opening through the web thereof having a housing the main 55 body of which is extended over and secured to the outer branch of the Z.

In testimony whereof I hereunto affix my signature.

JOSEPH LEDWINKA.
